IMPRESSION TAKING MEANS

Earl G. Coffey, Sioux City, Iowa

Original application February 18, 1946, Serial No. 648,220. Divided and this application February 21, 1946, Serial No. 649,199.

6 Claims. (Cl. 32—17)

1

This invention relates to means for taking impressions of the gums for producing upper dentures according to the method disclosed in my co-pending application, upon Dental technique, Serial No. 648,220, filed February 18, 1946, of which the present application constitutes a division.

Generally stated, the present invention embodies a dental tray into which plastic impression material of thin consistency may be forced, and mechanical means for securing the impression tray within the mouth and against the gums with a constant uniform pressure insufficient to cause distortion of the gums.

The invention consists in the novel form, combination and arrangement of parts, hereinafter more fully described, shown in the accompanying drawings and claimed.

In the drawings:

Figure 1 is a view, partly in side elevation and partly in section, showing means for taking impressions of the gums for producing an upper denture, which means is constructed in accordance with the present invention and illustrated as it appears in use.

Figure 2 is a perspective view of the head band employed for supporting the clamp used to hold the impression tray in position within the mouth.

Figure 3 is an enlarged perspective view of the clamp.

Figure 4 is an enlarged front perspective view of the keeper plate for the clamp.

Figure 5 is a rear perspective view of the device shown in Figure 4.

Referring in detail to the drawings, the present means or equipment includes a head band A, a spring clamp B supported by the head band, an impression tray C adapted to be held in proper position within the mouth and against the gums by the head band A and the clamp B, and a gun D for forcing the impression material into the tray C to fill the space between said tray and the gums.

The head band A comprises a main band member 5 adapted to be passed about the upper portion of the head in the region of the brow and equipped at one end with a suitable buckle 6 so that the band member 5 may be securely fastened in place. A crown strap 7 has its ends attached to the band member 5 so as to support the latter against downward creeping, particularly at the front and back of the head. At the front, the band member 5 is provided with a pair of adjacent, open-top pockets 8 for removable reception of the depending tongues 9 provided on and at

2

the back of a keeper plate 10 which has a pair of spaced keeper sockets 11 on the front thereof. In this way, the keeper plate is removably attached to the head band, and it is adapted to support the clamp B in a manner which will presently become apparent.

As shown, the clamp B includes a member formed from a single piece of wire to provide a substantially U-shaped jaw 12 which is curved downwardly longitudinally, and straight elongated spaced legs 13 extending from the ends of the jaw at an acute angle to the latter and in an upward direction. The legs 13 extend through apertures in a pair of spaced superposed finger plates 14 and 15, and separation of these finger plates is limited by means of stop lugs provided at 16 on the legs 13 beneath the plate 14. Plate 15 is attached to legs 13 at 17. The jaw 12 is provided at an intermediate point with a cross piece 18 of flexible wire. A pair of spaced rods 19 extend through further openings in the finger plates 14 and 15, and these rods are attached to plate 14 at 20 and have stop lugs 21 above plate 15 which limit separation of the plates 14 and 15. At their upper ends, the rods 19 are provided with hooked ends 22 adapted to be engaged in the sockets 11 of the keeper plate 10 to support the clamp B in proper position in front of the patient's face with the jaw 12 projecting rearwardly into the mouth. The lugs 16, 17 and 20, 21, by limiting separation of the finger plates 14 and 15, also limit movement of the hooks 22 toward the jaw 12. Encircling the legs 13 and rods 19 between the finger plates 14 and 15 are helical compression springs 23 and 24 which act to separate the plates 14 and 15 to the limit of separation and thereby normally contract the clamp B to a condition wherein the jaw is located at its limit of movement toward the hooks 22.

As before stated, the clamp B is utilized in connection with the head band A to hold the impression tray C in place within the patient's mouth and to press the tray against the gums with a limited amount of pressure so as to not cause the tray to distort the gums. The pressure may be properly adjusted in any suitable way and by any suitable means according to the conditions presented by each particular patient, such as by flexing the jaw 12 relative to the legs 13 toward or away from the hooks 22.

As shown in Figure 1, the tray C is generally of conventional form to provide the recess 25 for reception of the impression material. However, at the front, the tray is provided with a forwardly projecting nipple 26 which opens into the

recess 25 of the tray through the front of the latter as at 27, thereby permitting the impression material to be forced into the tray through said nipple while the tray is supported in proper position within the patient's mouth and against the gums. The nipple 26 is preferably of horizontally flattened form so as to comfortably protrude from the patient's mouth.

The gun 4 is of the syringe type and includes a cylinder or barrel 28 provided with removable caps 29 and 30 on the opposite ends thereof, the front cap 29 having a tapered flattened outlet nozzle 31 adapted to snugly fit in the nipple 26. Slidable in the cylinder or barrel 28 is the usual piston indicated by dotted lines at 32, said piston being carried by a rod 33 that slidably projects through a central aperture of the rear cap 30 and is equipped upon its rear end with a handle 34. The cap 30 carries a pair of finger rings 35. In practice, the cap 29 is removed and the piston 32 is retracted so as to permit filling of the barrel or cylinder 28 with the impression material in a state of thin consistency. Cap 29 is then replaced, and nozzle 31 is then inserted in the nipple 26, whereupon the piston 32 is forced forwardly so as to discharge the impression material into the tray C. In order to enable the operator to quickly determine when the space between the tray and the gums has been filled with impression material, said tray is provided along its rear edge with a series of apertures 36 through which the impression material may escape. As soon as the material appears at the apertures 36, the operator discontinues feeding of the impression material to the tray, so that there will be no extra impression material supplied which will run into the patient's mouth and cause discomfort or gagging. The tray C is provided at the bottom with transverse grooves 37 for selective reception of the intermediate transverse part of the jaw 12, while the cross piece 18 is arranged to bear against the under side of the tray C at the front thereof as shown in Figure 1. In this way, the clamp is effectively inter-engaged with the tray, and the latter is properly supported to bear uniformly against the gums throughout.

In use, after the required amount of impression material has been supplied to the tray, the gun is removed and the tray is allowed to remain in position until the impression material has set. Due to the thin consistency of the impression material, the manner in which it is supplied to the tray, and the manner in which the tray is held in position against the gums, no distortion of the gums takes place, and a true impression is had of the gums in an undistorted condition. This insures production of a denture which will not unduly press against the gums or distort them and which will accordingly remain tight in the mouth. As soon as the impression material has set, the clamp B and the tray C is removed, together with the head band A. It will be seen that the invention provides for the production of impression castings which are uniformly accurate, while requiring minimum amount of manual effort, skill and care. Plenty of time is allowed for performing the various steps, due to the fact that the impression material need not be prepared until after the tray is supported in proper position, and due to the fact that the impression material is supplied to the tray while in a state of thin consistency. Minor changes may be made in details of construction, such as fall within the scope of the invention as claimed.

What I claim is:

1. An impression taking device including a tray for use in taking impressions of the gums in producing complete upper dentures, said tray being provided at the bottom with a transverse groove, and means for securing the tray within the patient's mouth and yieldingly pressing said tray against the gums, said means comprising a head band and a spring clamp suspended from the front of said head band and having a rearwardly extending lower jaw spring-pressed upwardly and embodying a transverse part adapted to seat in said transverse groove of the tray.
- 10 2. An impression taking device including a tray for use in taking impressions of the gums in producing complete upper dentures, said tray being provided at the bottom with a transverse groove, and means for securing the tray within the patient's mouth and yieldingly pressing said tray against the gums, said means comprising a head band and a spring clamp suspended from the front of said head band and having a rearwardly extending lower jaw spring-pressed upwardly and embodying a transverse part adapted to seat in said transverse groove of the tray, and a cross-piece arranged forwardly of said transverse part to bear against the underside of the tray near the front of the latter.
- 20 3. An impression taking device including a tray for use in taking impressions of the gums in producing complete upper dentures, and means for securing the tray within the patient's mouth and yieldingly pressing the tray against the gums, said means comprising a head band and a spring clamp suspended from the front of said head band and having a rearwardly extending lower jaw spring-pressed upwardly and having a transverse part adapted to engage and extend across the underside of said tray.
- 30 4. An impression taking device including a tray for use in taking impressions of the gums in producing complete upper dentures, and means for securing the tray within the patient's mouth and yieldingly pressing the tray against the gums, said means comprising a head band and a spring clamp suspended from the front of said head band and having a rearwardly extending lower jaw spring-pressed upwardly and having a transverse part adapted to engage and extend across the underside of said tray, and a cross-piece arranged on said lower jaw to bear against the underside of the tray near the front of the latter.
- 40 5. The construction defined in claim 3, wherein the head band is provided at the front with a pair of spaced sockets, said clamp further including upper rod members provided with upper downwardly directed hooked ends removably engaged in said sockets.
- 50 6. An impression taking device including a tray for use in taking impressions of the gums in producing complete upper dentures, and means for securing the tray within the patient's mouth and yieldingly pressing the tray against the gums, said means comprising a head band and a spring clamp suspended from the front of said head band and having a rearwardly extending lower jaw spring-pressed upwardly and adapted to engage the underside of said tray, said clamp including a lower member formed from a single piece of wire to provide the lower jaw in substantially U-shape and curved downwardly longitudinally, and spaced elongated straight legs extending upwardly from the ends of said jaw, a pair of spaced superposed finger plates through which said legs
- 60 70 75 extend, the upper one of said finger plates being

attached to said legs and the lower one thereof having the legs slideable therethrough, a pair of spaced rods extending through said finger plates, the lower one of said finger plates being attached to said rods and the upper one thereof having the rods slideable therethrough, stop lugs on the legs beneath the lower finger plate and on the rods above the upper finger plate to limit separation of said finger plates, compression springs on the legs and rods between the finger plates, said rods having hooked upper ends, and sockets on the front of the head band in which said hooked ends are removably engaged.
